F. W. KUHNERT, OF ROCHESTER, NEW YORK.

Letters Patent No. 65,093, dated May 28, 1867.

IMPROVED RUDDER.

The Schedule referred to in these Letters Patent and making part of the same.

TO ALL WHOM IT MAY CONCERN:

Be it known that I, F. W. KUHNERT, of Rochester, in the county of Monroe, and State of New York, have invented a certain new and useful Improvement in Rudders for Ships; and I do hereby declare that the following is a full and exact description thereof, reference being had to the accompanying drawings, making part of this specification.

Figure 1 is an elevation of a steamship provided with my improvement.

Figure 2 is a plan of the same.

Figure 3 a section of the keel in the plane of line $z z$, fig. 1.

Like letters of reference indicate corresponding parts in all the figures.

My invention consists in combining, with the ordinary rudder of a ship, a series of auxiliary rudders arranged successively one after another in the keel, occupying such an extent or length as to act in conjunction with the main rudder in producing a more ready and sensitive action of the ship in turning the said series of rudders, being so connected with the windlass of the main rudder that they may be attached or detached at pleasure. Also the employment, in connection with the above, of an auxiliary rudder in front of the vessel, the same being applicable more particularly to war vessels requiring quick movements.

As represented in the drawings, A is a ship or vessel, having the usual rudder B, operated by chains connected with steering-wheel C in the ordinary manner. In the keel D is arranged a series of auxiliary rudders, E E E, extending forward successively, one after another, as shown in figs. 1 and 3, each being independent of the others and having a separate action in itself. These rudders may be operated by any desirable means, that indicated in the drawings (dotted lines) being chains attached to crank-arms of the rudders on each side, and passing forward, joining together, and having a hook or equivalent, α , which hooks into an eye or ring, b , of the chain connecting with the steering-wheel that operates the main rudder. When it is desired to disconnect the auxiliary rudders from action, the hook α is slipped from b to a dead-eye, f .

These auxiliary rudders, by occupying an extended length in the keel, serve, in conjunction with the main rudder, to produce a more sensitive and positive action on the ship than can be produced by the main rudder alone. They act in this manner not only by reason of their extended length, but also from their peculiar position beneath the ship, where they are situated at such a depth that the water cannot be displaced as at the rear and near the surface. Therefore, the maximum resistance is produced to the rudders when set at any angle. By this arrangement I am enabled to extend the rudder action, if desired, nearly half the length of the ship. This is of much importance under many circumstances, for instance in a gale. If at any time the main rudder becomes impaired or useless, the auxiliaries still remain intact, and being situated so deep they are but little exposed. The means described of disconnecting the action of the auxiliaries by hook α is very simple and effective. In calm weather, and under ordinary circumstances, only the main rudder is required. When desired the others can be connected in a moment's time. In the front end of the ship is situated another auxiliary rudder, G, operated by hand-wheel, H, or in any equivalent manner. This is effective in producing a quick turn. It is intended for use more particularly in those cases of emergency where it is necessary to make rapid changes of position. It would be very effective in war vessels.

I am aware that the main rudder of ships has before been provided with supplementary wings forming a part of itself. I am also aware that it has been proposed to employ "one or more" screws to steer the vessel. Such I do not claim, but what I claim as my invention, and desire to secure by Letters Patent, is—

The combination, with the main rudder B, of the series of auxiliary rudders E E E, arranged in the keel one after another, and capable of being connected with and disconnected from the main rudder in action, as herein set forth.

In witness whereof I have hereunto signed my name in the presence of two subscribing witnesses.
